CLAIM

(57) The ornamental design for a keyboard solar panels, as shown and described.

DESCRIPTION

The sole FIGURE is a top plan view of a keyboard solar panels showing our new design.

The broken lines shown represent unclaimed subject matter only and form no part of the claim. Where broken lines abut a claimed surface it is understood that those broken lines represent an unclaimed boundary between claimed and unclaimed surfaces. None of the broken lines form any part of the claimed design.
